(57) **CLAIM**

The ornamental design for a gas sampling pump, as shown and described.

DESCRIPTION

FIG. 1 is a perspective view of the gas sampling pump showing my new design;

FIG. 2 is a front elevational view thereof;

FIG. 3 is a top plan view thereof;

FIG. 4 is a bottom plan view thereof;

FIG. 5 is a left side elevational view thereof; and,

FIG. 6 is a right side elevational view thereof.
